UNITED STATES PATENT OFFICE.

GEORGE U. ROULET, OF TOLEDO, OHIO.

DESIGN FOR A SPOON, &c.

SPECIFICATION forming part of Design No. 22,059, dated December 20, 1892.

Application filed October 19, 1892. Serial No. 449,402. Term of patent 7 years.

To all whom it may concern:

Be it known that I, GEORGE U. ROULET, a citizen of the United States, residing at Toledo, county of Lucas, and State of Ohio, have invented and produced a new and original Design for Spoons and Like Articles, of which the following is a specification, reference being had to the accompanying drawing, showing a part thereof.

10 The leading feature of my design consists in the handle formed in the representation of a chimney, surmounted by Santa Claus carrying a pack, and another feature of my design consists in the bowl ornamented with a representation of the birth of Christ in a stable.

15 The drawing hereunto annexed clearly illustrates my invention, and referring to this drawing for further description of my design.

1 indicates the bowl of the spoon, and 2, 20 the handle of the same. This handle is produced in the representation of a chimney, and is surmounted by the representation of Santa Claus carrying his pack of toys. Near

the top of the handle is produced the representation of a snow bird and a bunch of holly, 25 and at the bottom of handle is also produced a representation of holly leaves and berries. The bowl 1, is ornamented by a representation of the birth of Christ in a stable, the Child Jesus being shown upon His cradle with 30 the Virgin Mary close by, while the attending shepherds are grouped about the mother and child. A representation of the Star of Bethlehem shedding its rays upon the Child Jesus is also produced upon the bowl.

35 Having thus described my invention, what I claim is.

The design for a spoon, substantially as herein shown and described.

In testimony that I claim the foregoing as 40 my own I hereby affix my signature in presence of two witnesses.

GEORGE U. ROULET.
